7 Claims. (Cl. 302—28)

This invention relates to improvements in arrangements of conveying and feeding fibrous raw materials such as cotton-wool in a spinning machine.

One object of this invention is to provide arrangements for conveying and allotting fibrous raw material delivered to a plurality of receiving means automatically by means of air stream.

Another object of this invention is to provide arrangements of the class described which are capable of allotting the fibrous raw material evenly to all receiving means and in which the fibrous raw material flows freely.

Another object of this invention is to provide arrangements of the class described in which the fibrous raw material circulates through passages while being conveyed by air, and during its passage the material is allotted into receiving means.

Briefly stated in accordance with one aspect of this invention, there is provided an arrangement of a spinning machine, comprising a main duct through which fibrous raw material is conveyed by means of air stream, and a plurality of branch ducts branched out of the main duct, through which the conveyed material is allotted into a plurality of receiving means, each of said branching points being provided with a resisting block.

The invention will be better understood and other objects and additional advantages of the invention will become apparent upon perusal of the following description taken in connection with the drawings.

In the drawings, FIG. 1 is a schematic elevation of a spinning machine embodying this invention, showing a conveying system for a fibrous raw material;

FIG. 2 is a sectional elevation of a receiving means; FIG. 3 is a front elevation thereof;

FIG. 4 is a partly sectional elevation of a disjointing means;

FIG. 5 is a plan view thereof;

FIG. 6 is an enlarged vertically sectional view thereof taken along lines A'—A' of FIG. 5;

FIG. 7 is an enlarged horizontally sectional view thereof taken along lines B'—B' of FIG. 6; and

FIG. 8 is an enlarged vertically sectional view thereof taken along lines C'—C' of FIG. 7.

Referring more particularly to the drawings, the preferred embodiment of this invention will now be described; however, this description will be understood to be illustrative of the invention and not as limiting it to the particular construction shown and described. In FIGS. 1, 2 and 3, a receiving means D is shown. Main duct C leads from mixing and scutching means A to hoppers 2. Cotton is admitted into the duct C and is conveyed through the duct by means of an air stream supplied by blower 1, cotton being distributed to the hoppers in the following manner. The main duct C is communicated with the hopper 2 through an inlet 3. The bottom of the main duct C has a down slope 4 to the inlet 3 so as to enlarge the section of the main duct C thereto gradually. There is an expanded portion 5 of the top of the main duct C arranged above the hopper 2 so as to prevent the main duct C from cotton clogging

about the inlet 3. A subsidiary passage 6 is provided to communicate the main duct C with the hopper 2. Its upper end is tilted so as to form a subsidiary air stream. Between the inlet 3 and the subsidiary passage 6 a hollow resisting block 7 having a front wall 7' and a rear wall 7'' is positioned. A filter netting 8 made of metallic material, glass fibre, vinyl resin thread, etc. is positioned across the lower part of the subsidiary passage 6 in order to prevent the cotton allotted to the hopper 2 from the main duct C from counterflowing thereto. A compressed air nozzle 9 is provided within the upper part of the subsidiary passage 6 and arranged downwardly so as to blow off cotton clogged on the filter netting 8 and to ensure the subsidiary air stream through the subsidiary passage 6 by means of an intermittent air stream ejected by the compressed air nozzle 9 which is communicated with a compressed air source such as a compressor through a compressed air pipe 10 and a branch thereof 10'. It is preferred that the upper half of the hopper 2 is individually constructed from the main duct C so as to be removable from the latter disengaging the flange 11 with the latter. The lower half 2' of the hopper 2 is telescopically constructed so as to be adjustable in height. By virtue of such a construction, arranging the main duct along the ceiling of the mill and a carding frame on the floor of the mill, it becomes possible to adjust the distance between the main duct C and taking up a pair of wood rollers 12 arranged under the bottom of the hopper 2. The above construction facilitates the flow of the air stream from the main duct C into the hopper 2 so as to supply cotton to the latter, excess air being returned to the main duct C through the subsidiary passage 6 so as to join the main stream, whereby it becomes possible to convey and allot cotton to the hoppers 2 smoothly and surely.

In FIGS. 4 through 8, a separator B is illustrated. Raw cotton-wool delivered from the mixing and scutching means A in a sliver form by lap rollers 41 is directed to this separator B. Numeral 42 indicates a feeding means having a width corresponding to the raw cotton 52 being delivered at the inlet end. Feeding means 42 is directioned towards main duct C in the form of a funnel shape, as is shown in FIG. 5. Blow-off means 43 for directing air against the delivered cotton 52 is supplied with air by means of blow-off 45 and blast pipe 44. Blow-off means 43 comprises a slit 53 provided in the wall of the feeding means 42 and several nozzles 51. The latter is so devised that, for example, it is displaced continuously in a direction at a right angle to that of the transfer of the cotton 52, whereby the transferring cotton 52 is torn to pieces having a predetermined size. Numeral 1 indicates a main blower whence air is directed to the main duct C through which the torn cotton 52 is conveyed by the air. Numeral 48 indicates a motor to drive the blower 45. In the blow-off means 43, there is an endless belt 49 carrying the nozzles 51 which are displaced along the slit 53 of the feeding means 42 continuously. Belt 49 is driven and held by pulleys 50 and 50'. The slit 53 may be provided in and across the lower wall of the feeding means 42 or in and across the both walls thereof, is covered by the blow-off means 43 and is further kept air-tight by the endless belt 49 so as to jet air effectively only through the nozzles 51. A suitable casing 54 covers the blow-off means 43 and a part of the feeding means 42. The raw cotton 52 is thus torn to predetermined even pieces by the moving jet air generated by the nozzles 51 moving in a direction at a right angle to the travel of the cotton, conveyed to the outlet of the feeding means 42, and further conveyed through the main duct C by the air delivered by the main blower 1, or a conveyor. Therefore, movement in the

main duct C becomes smooth and even and equally sized pieces of cotton are conveyed for feeding to every hopper. The blast generated by the blower 45 directed against the cotton by means of preferably inclined nozzles 51 serves to assist the conveyance in the main duct C. The slits 53 may readily be provided in the optional wall of the feeding means. The casing 54 may be made simply. Therefore, such a construction is very inexpensive. C' is a return duct, while G is a reverse tank.

What we claim is:

1. A fibrous material feeding means comprising a duct, through which said fibrous material is conveyed by means of an air stream, and a resisting block positioned at a branching point of said duct to receiving means so as to direct a portion of said material to said receiving means, said resisting block having a continuous front wall on the side of air-fiber impingement and being positioned at an intermediate cross-section of said duct so as to deflect air while defining upper and lower channels for fluid flow about said resisting block and defining a subsidiary passage communicating said duct with said receiving means along the rear wall of said resisting block.

2. A fibrous material feeding means as claimed in claim 1, which comprises a filter provided across said subsidiary passage.

3. A fibrous material feeding means as claimed in claim 1, which comprises a filter provided across said subsidiary passage and a nozzle for jetting compressed air against said filter within said subsidiary passage.

4. A fibrous material feeding means as claimed in claim 1, which comprises a separator in which raw fibrous material delivered in a sliver-like form is torn successively into a plurality of pieces of predetermined size by means of jets of compressed air, and then fed into said duct for conveyance.

5. A fibrous material feeding means as claimed in

claim 1, which comprises a separator in which raw fibrous material delivered in sliver-like form is torn successively into a plurality of pieces of predetermined size by means of jets of compressed air, discharged by continuously displaced nozzles moving across the path of fibrous material flow, said fibrous material then being fed into said duct for conveyance.

6. A fibrous material feeding means comprising a duct through which said fibrous material is conveyed by means of an air stream, and a resisting block provided at a branching point of said duct to a receiving means so as to direct a portion of said material to said receiving means, said resisting block having a continuous front wall on the side of air-fiber impingement and being fixedly positioned at an intermediate cross section of said duct so as to deflect air while defining an annular channel for fluid flow about said block.

7. A fibrous material feeding means which comprises a separator in which raw fibrous material is delivered in sliver-like form, a plurality of continuously displaced nozzles moving across the path of fibrous material flow in said separator, means for forcing jets of air through said continuously displaced nozzles so as to successively tear said raw fibrous material into a plurality of pieces of predetermined size, and means for passing said torn fibrous material into a duct for conveyance.
